UNITED STATES PATENT OFFICE.

ARTHUR J. HOWARD, OF MELDEN, MASSACHUSETTS, ASSIGNOR TO THE WIRE GRIP FASTENING COMPANY, OF CHICAGO, ILLINOIS.

DESIGN FOR A NAIL OR SLUG.

SPECIFICATION forming part of Design No. 24,765, dated October 15, 1895.

Application filed September 16, 1895. Serial No. 562,725. Term of patent 14 years.

To all whom it may concern:

Be it known that I, ARTHUR J. HOWARD, of Malden, in the county of Middlesex and State of Massachusetts, have invented and produced 5 a certain new and useful Design for a Nail or Slug, of which the following is a specification, reference being had to the accompanying drawings, forming a part thereof—

Figure 1 is an isometric view of a nail or 10 slug, showing my design; and Fig. 2 is an end view thereof.

My design relates to nails or slugs for ornamenting the heels of boots and shoes.

The leading feature of my design consists 15 in the longitudinal grooves formed in opposite sides of a nail or slug, one side of each groove being plane and the other side curved, forming a narrow fin between a substantially quadrilateral prismatic portion and a cylindrical portion tangent thereto.

The nail or slug is grooved or cut longitudinally in opposite sides at k between a cylindrical portion k' and a tangent quadrilateral prismatic portion k^2 , the portion k' forming one curved side of each groove, while the tangent face of the prism k^2 forms the straight side of each groove, the grooves k leaving the narrow fin k^3 along the line of tangency. 25

I claim—

The design for a nail or slug substantially 30 as set forth.

In testimony whereof I have signed my name to this specification in the presence of two subscribing witnesses.

ARTHUR J. HOWARD.
